WELL FISHING TOOL

Alexander T. Cooper, Long Beach, Calif., assignor
to Acme Patent Development Corporation,
Long Beach, Calif., a corporation of California

Application January 13, 1940, Serial No. 313,749

7 Claims. (Cl. 294—86)

This invention relates to oil well equipment and more particularly to a fishing tool for removing lost objects from a well.

In drilling a well with the rotary system parts of drilling bits often become detached therefrom, such as cones, pieces of the bit itself, nuts, washers and other objects. If such objects are not removed from the well they materially impede further drilling operations.

Apparatus has heretofore been devised for the above stated purpose, and while such apparatus serves their intended purpose their capacity is somewhat limited, it often being necessary to make more than a single trip down the well to recover all of the lost "junk."

It is therefore an object of this invention to provide an apparatus of the character described in which the article recovery mechanism may be quickly operated to engage lost objects from a well and then reset for another operation after removing the same.

Another object is to provide a fishing tool so constructed that the "fish" engaging or article recovery mechanism will occupy little space when set for a "fish" removing operation thereby enabling the same to not only engage larger objects than heretofore possible, but have greater capacity.

A further object is to provide a fishing tool of the character described constructed in such a manner that a basketlike structure is formed when the tool is operated thereby collecting both small and large objects and retaining the same while the tool is being removed from the well.

A still further object is to provide a well fishing tool that is of simple and economical construction which may be readily operated to recover lost articles in a well.

Other objects and advantages will be apparent from the following disclosure, reference being had to the accompanying drawing in which

Fig. 1 is a vertical section taken through the improved fishing tool in a well hole showing the parts as they appear prior to a fish engaging operation.

Fig. 2 is a fragmentary section similar to Fig. 1 showing them as they appear after the catcher has been operated.

Fig. 3 is an enlarged perspective view in section of the catcher.

Fig. 4 is a horizontal section taken on line 4—4 of Fig. 3, but showing the catcher as it appears after being operated.

Fig. 5 is a detail section taken on line 5—5 of Fig. 4.

Referring more specifically to the drawing 10 generally designates the improved fishing tool disposed in a well H, in the present instance it is shown connected through a tool joint T to a string of drill pipe D.

It will be understood that the tool may be connected to a steel cable or sand line and operated by a set of jars connected thereto in a manner hereinafter described.

10 Removably secured to the lower end of tubular casing 12 preferably by screw threads 13 is the article recovery mechanism or catcher 14 which is operated through engagement with the head 15 of a plunger 16 square shaped in cross section 15 slidably mounted in a correspondingly shaped opening formed in a plug 17 connected to the upper end of the tubular casing 12.

Plug 17 is provided with a plurality of fluid circulating openings 18 while the bar 16 has a fluid passage 19 therethrough for the circulating mud and is provided with a pin 20 for connection with the box 21 of the tool joint T.

20 The article recovery mechanism 14 consists of a base member 22 having an internal concave face 23 and an upper member 24 having a convex face 25 mounted thereon which when assembled form an annular arcuate channel or guide way indicated at 26 which serves to bend or turn inwardly a plurality of prongs or flat fingers 27

30 when the mechanism is operated. The upper member 24 has a lateral flange 28 in which is formed a plurality of slots 30 into which project the pointed ends 31 of the prongs 27 when the mechanism is assembled for a fishing operation 35 as shown in Figs. 1 and 3, the upper member being secured by screws 32 to the base.

Prongs 27 are preferably formed of a pliable material such as sheet steel employed in die stamping operations, and are secured at their 40 upper ends to a ring 34 preferably by welding as indicated at 35, it being noted that the prongs are curved in cross section on a radius corresponding to the slots 30 in order to add strength to the same after they have been bent into a 45 "fish" engaging position as shown in Fig. 2.

Formed on the lower end of the base member 22 is a row of teeth 22a which serve to penetrate the formation and loosen any earthy material that may have settled around the "fish" on the 50 bottom of the hole, the tool being rotated and circulating fluid pumped therethrough at this time. The head 15 of the plunger is held out of engagement with the mechanism 14 after assembling until it is desired to operate the same by a

55 sheer pin 36 that is mounted in the wall of tube

12 the projecting end being disposed in a recess
31 formed in the side wall of the head.

In use the improved fishing tool is connected to the drill pipe T and lowered into the well until it rests on the bottom, if the "fish" or other lost objects have become embedded below accumulated earthy cuttings, the drill pipe is then connected with a hydraulic swivel and the pipe rotated until the earthy material has become loosened sufficiently to permit the prongs of the apparatus to be disposed beneath the "fish."

The draw works brake (not shown) is then released whereupon the dead weight of the drill pipe on its downward movement causes the head 17 on bar 16 of the plunger to engage the ring 34 and force it downwardly, such action bending the prongs 27 and closing them around the "fish," due to the curvature of the channel or guideway 26.

Thus it will be seen that when ring 34 is pressed downwardly as above described a substantially basket-like structure is formed (see Fig. 4) at which time the prongs 27 pass underneath the "fish" as shown in Fig. 2, the prongs being shown (in Fig. 4) as they appear after being forced downwardly and inwardly when the tool is out of the well, it being particularly noted that due to the construction the area of the opening in the mechanism 14 is practically closed after the above described operation thereby engaging both large and small objects. Also the structure is strengthened due to inner end of the prongs being in overlapping relation.

When removing "fish" that have not been in the well hole for any great length of time or have not become covered with sand or other earthy material the fishing tool is adapted to be connected to a steel cable or sand line with a set of jars (not shown) connected to the pin 21. After the tool has reached the bottom of the hole the jars are actuated a number of times, the action of which closes the prongs around the "fish" as above described.

After completing a fishing operation the tool 10 is removed from the well, the catcher 14 is discharged of the recovered "fish" after which the tool is reset for another operation. This is accomplished by placing the catcher 14 over or inserting a bar into it of such diameter that it will pass through ring 34 and engage the face of flange 28, then holding the ring stationary and pushing on the bar or vice versa the action of which separates the ring from the base members 22 and at the same time straightens the prongs 27. The prongs may then be inserted in the slots 30 and the catcher 14 screwed into the tube 12. It will be noted that due to the prongs being formed of pliable metal they may be bent and straightened many times without injury.

It will be understood that after an operation instead of straightening the prongs as above described the pronged members may be readily replaced by another unused member, thus conserving the time between succeeding operations.

I claim:

1. A fishing tool for wells comprising a member having a central opening and a downwardly converging surface, a second member having a downwardly converging surface opposed to said first-mentioned surface and spaced therefrom to form a circumferentially continuous annular channel, a plurality of circularly spaced bendable prongs having their free ends extending downwardly into said channel, a mounting member to which said prongs are secured, a tubular member con-

nected to said first-mentioned member, and a plunger movable downwardly within said tubular member to engage said mounting member and force said prongs down through said channel, whereby they will be bent to extend radially across said central opening to form an article holding structure.

2. An apparatus of the class described comprising a base member having a central opening and a downwardly converging concave surface, an upper member having a flange secured to said base member and a downwardly converging convex surface spaced inwardly from said concave surface to form a downwardly and inwardly curving channel, an annular member having a plurality of bendable prongs detachably secured thereto, the free ends of said prongs projecting downwardly into said channel, a tubular member connected to and extending upwardly from said base member, a plug secured to the upper end of said tubular member, a plunger slidably mounted in said plug and movable downwardly in said tubular member into engagement with said annular member to force said prongs through said channel, whereby they will be bent to extend radially across said central opening to form an article holding structure, said annular member engaging said upper member to limit the radial projection of said prongs across said opening.

3. An apparatus of the class described comprising a member having a plurality of vertical circularly spaced bendable prongs, a base member having a downwardly converging circumferentially continuous channel formed therein into which the free ends of said prongs project, a tubular casing detachably connected to said base member, a plug detachably secured to the upper end of said tubular member, a plunger 40 slidably mounted in said plug, a plunger head secured to said plunger and movable downwardly within said tubular member into engagement with said prong member to force the prongs downwardly through the channel, whereby to bend them toward each other to form an article engaging structure.

4. A fishing tool for wells comprising a cylindrical base member having a central opening in its lower end and a downwardly converging inner surface with an annular row of cutting teeth therebelow, a companion member having a downwardly converging surface opposed to said base member and spaced therefrom to form a circumferentially continuous channel therebetween detachably secured to said base member, a plurality of bendable spaced prongs having their free ends engaging the channel formed between the base and said companion member, an annular mounting member to which said prongs are secured, a tubular member connected to said base member, a plug connected to the upper end of said tubular member, and a plunger splined to said plug to rotate the tubular member and force the prongs downwardly through the channel whereby to bend and force them to extend across the central opening of the circular member to form an article holding structure.

5. An oil well fishing tool comprising a tubular casing, a circular member having a central opening and a downwardly converging surface detachably secured to the lower end of said casing, a second circular member detachably secured to said first mentioned member having a downwardly converging surface and spaced therefrom to form a circumferentially continuous annular

channel, an annular independently removable prong mounting member having a plurality of bendable prongs secured thereto, their free ends engaging the circumferential annular channel formed by the circular members, and a plunger movable downwardly within said tubular casing to engage the prong mounting member to force the prongs secured thereto downwardly and outwardly through said annular channel whereby to bend the prongs to extend across the central opening of the circular members to form an article holding structure.

6. In a fishing tool, the combination of: a cylindrical casing open at the lower end and provided with an interior annular concave surface adjacent the lower end; a ring held within the casing adjacent the lower end thereof, said ring being provided with an exterior convex surface in spaced relation to the aforesaid concave surface to form a channel therebetween; a collar within the casing and movable longitudinally of the casing, said collar being provided with a plurality of downwardly extending deformable prongs; ports in said ring adapted to guide said prongs into said channel; and means movable within the casing and adapted to strike the collar to force said prongs through said channel and

guidingly deform the same inwardly into overlapping relation, said ring being adapted to cooperate with said collar to stop downward movement of the collar.

- 5 7. In a fishing tool, the combination of: a cylindrical casing open at the lower end and provided with an interior annular concave surface adjacent the lower end; a ring held within the casing adjacent the lower end thereof, said ring being provided with an exterior convex surface in spaced relation to the aforesaid concave surface to form a channel therebetween; a collar within the casing and movable longitudinally of the casing, said collar being provided with a plurality of downwardly extending deformable prongs having substantially parallel side edges; ports in said ring adapted to guide said prongs into said channel; a plug carried by the upper end of the cylindrical casing, a stem of polygonal section extending slidably through said plug, a head carried by said stem within said casing, and frangible means for restraining movement of said head within the casing, said head being movable to strike the collar to force said prongs through said channel and guidingly deform the same inwardly into overlapping relation.
